TALBOT C. DEXTER, OF PEARL RIVER, NEW YORK, ASSIGNOR TO DEXTER FOLDER COMPANY, OF PEARL RIVER, NEW YORK, A CORPORATION OF NEW YORK.

PAPER-FEEDING MACHINE.

1,098,234.

Specification of Letters Patent. Patented May 26, 1914.

Application filed February 11, 1911. Serial No. 608,117.

To all whom it may concern:

Be it known that I, TALBOT C. DEXTER, a citizen of the United States, and resident of Pearl River, in the county of Rockland 5 and State of New York, have invented certain new and useful Improvements in Paper-Feeding Machines, of which the following is a full and clear specification.

The recent development and extensive introduction of rapidly operating rotary printing presses has necessitated material changes in the construction and operation of automatic paper feeding machinery, particularly with regard to correcting the irregularities 10 in position of the successive sheets of a pile due to the uneven piling of the sheets upon which the feeler operates. Under the old practice, in which relatively slow operating presses were largely used, it was perfectly 15 feasible to accurately straighten the successive sheets of paper upon the conveyer frame between the feeding machine and the gages of the press. This straightening operation was also usually facilitated by the employment 20 of automatically controlled feeding-off devices in the feeding machine by which the successive sheets were delivered from the pile to the conveyer frame in fairly straightened condition. This practice is no longer 25 possible when feeding sheets to the rapid rotary press for the reason that the sheets have to be moved so rapidly that there is not sufficient time to effectively straighten 30 them upon the conveyer frame. This change 35 in the practical conditions in the art has necessitated a simplification of the automatic feeding machine with a view to increasing its speed of operation and the elimination of the old forms of sheet straightening 40 devices. This reorganization of printing and feeding mechanism does not alter the necessity for some reliable means to insure the straightening or squaring of the sheets prior to their arrival at the press 45 gages, since it is practically impossible, for obvious reasons, to rely upon the movement of the sheet against the gages to effect the squaring of the sheet. In fact the movement of the sheets is so rapid over the conveyer 50 frame that an effective slow down mechanism must be employed to prevent the rebound of the sheets from the gages or the injury of the leading edge of the sheets by

the gages. These difficulties are overcome by my present invention by which the successive sheets fed from the pile of an automatic feeding machine are accurately squared and straightened just prior to the delivery of the sheets from the feeding machine to the conveyer. This sheet straightening operation can be accomplished in any feeding machine having a simple feeding-off device with a regular feeding stroke, by providing, at the delivery end of the machine, suitable auxiliary frictional feeding devices adapted 55 to receive the leading edge of the sheets advanced from the pile by the feeding-off devices and give the sheets a delicate forward feeding impulse to bring them in contact with suitable sheet straightening gages 60 which are presented across the path of the sheets. These straightening gages and co-operating auxiliary feeding devices are arranged upon opposite sides of the central longitudinal plane of the machine and the 65 engagement of the auxiliary feeding devices with the sheets is so delicate that the sheets 70 will be accurately moved into contact with the straightening gages but will not be injuriously crowded against the gages. The 75 result of this construction will be the effective straightening of the sheets against the gages, since each auxiliary feeding device only moves the sheet sufficiently to bring the edge in front of it against one of the 80 gages and then operates idly upon the sheet until both auxiliary feeding devices are automatically thrown out of action. Suitable 85 guiding plates or fingers are arranged above and below the plane of feed of sheets to confine the sheets at their leading edge adjacent to the gages and prevent them from buckling. In addition to the auxiliary feeding devices and straightening gages, I employ in the same zone the usual drop roller 90 delivery mechanism, and suitable operating mechanism therefor so arranged that when the straightening gages and auxiliary devices are in action the drop rollers are held 95 out of action and when the drop rollers are operated to deliver a sheet the straightening gages and auxiliary feeding devices are automatically thrown out of action. The best 100 results are obtained by arranging the auxiliary frictional feeding devices as close as 105 possible to the straightening gages. In prac-

tice the auxiliary feeding devices are preferably in the form of frictional rollers, although feed belts and rollers can sometimes be effectively employed.

5 In order that my invention may be fully understood I will first describe the same with reference to the accompanying drawings and afterward point out the novelty more particularly in the annexed claims.

10 In said drawings Figure 1 is a detail front elevation, partly broken away, of an automatic paper feeding machine embodying my improvements. Fig. 2 is a detail, vertical, longitudinal sectional view of the same, taken on the line 2—2 of Fig. 1. Fig. 3 is a similar view taken on the line 3—3 of Fig. 1. Fig. 4 is a detail plan view of part of one of the auxiliary feeding devices. Fig. 5 is a view similar to Fig. 2 showing a modification of the invention.

15 1 and 2 represent the main side frames of an automatic paper feeding machine which may be of any suitable construction. Operating within this frame is the usual vertically movable pile support (not shown) upon which is mounted a pile of sheets indicated at P.

20 3 indicates one of the series of vertical pile gaging plates or bars.

25 30 A transverse shaft 5 is suitably journaled in the side frames 1 and 2 and extends transversely of the machine in front of the pile gages 3. This shaft 5 carries a series of main under feed rollers 10, the shaft 5 being continuously driven by any suitable gearing such as illustrated in the drawings. Co-operating with two of the main under feed rollers 10 upon opposite sides of the central longitudinal plane of the machine are the 35 usual drop rollers 15, freely journaled upon the rear ends of rock arms 16 mounted upon a rock shaft 17 which is journaled at its ends in the side frames 1 and 2 and carries adjacent to one end a rear crank arm 18, pivoted at 19 to pitman 20 formed with a yoke shaped upper end 21. The main cam shaft of the machine is indicated at 25. This shaft carries a controlling cam 22 with which engages an anti-friction roller 23 40 journalled upon the pitman 20. A spring actuated rod 24 engages a forward crank arm 18^a, projecting from rock shaft 17 to throw the drop roller 15 downwardly under the control of the cam 22.

45 50 55 60 65 30 is a rock shaft journaled in the side frames 1 and 2 and extending transversely of the machine above the pile of sheets. This rock shaft 30 has motion imparted to it by any suitable means (not shown), and supports and actuates the feeding-off devices which may be of any suitable construction. In the drawings I have shown a feeding-off device of the general construction covered by Patent No. 768,979, dated August 30th, 1904, in which a depending rock arm 31 has

70 75 80 85 90 95 100 105 110 115 120 125 mounted upon its lower end the frictional feeding-off fingers 32. The particular construction of the feeding-off devices is immaterial to the present invention. Adjacent to and in the same zone as two of the main under feed rollers 10 upon opposite sides of the central longitudinal plane of the machine, I mount curved guide plates 40 upon the upwardly projecting bracket arms 41, which are supported by the transverse tie bolt 42. These guide plates 40 have their rear ends curved downwardly to bring them slightly within the periphery of the main under feed wheels 10. Above the lower guide plates 40 I arrange similar curved guide plates 45 which are supported upon the depending bracket arms 46 mounted upon the transverse tie bolt 47. The rear ends of these upper guide plates 45 are curved upwardly and form with the lower guide plates a gradually contracting throat into which the successive sheets are passed by the feeding-off devices.

5 fingers 65 will rock arms 62 for raising friction wheels 63 away from the auxiliary feed wheels 55. When the main drop rollers are raised out of action the springs 64 will return the friction wheels 63 to their engagement with the under friction wheels 55.

70 is a rock shaft extending transversely of the machine and supported in bracket arms 71 extending up from the tie bolt 42.

- 10 This rock shaft 70 has secured to it the upwardly projecting gage fingers 75 which are adapted to project vertically across the path of sheets in front of the parallel portions of the guide plates 40 and 45. The rock shaft 70 has secured to it a short rock arm 76 which is pivotally connected at 77 to a connecting rod or link 78 pivoted at 79 to a rearwardly presented rock arm 80 adjustably mounted upon the main drop roller rock shaft 17. 20 The result of this construction will be that when the drop rollers 15 are lowered into action for delivering a sheet from the pile the sheet straightening gages 75 will be moved out of the path of sheets so as to permit the sheets to move freely from the machine, and when the drop rollers are raised out of action the sheet straightening gages will be presented across the path of sheets. 25 The two positions of the straightening gages 30 are shown in Fig. 2 of the drawings.

35 is the usual tape roller of the sheet conveyer frame which is adapted to receive successive sheets from the feeding machine and convey them to the gages of the printing press, folding machine or other machine designed to operate upon the sheets.

In Fig. 5 of the drawings I have shown a slight modification of my improved sheet straightening mechanism. In this form of 40 the mechanism I employ two short endless belts 90 which pass around main and auxiliary under feed wheels 10 and 55 mounted as above described with reference to the preferred form of the mechanism excepting 45 that the bracket arms 51 are adjusted to present the auxiliary under feed wheels 55 a little farther forward than in the preferred form. The drop roller delivery mechanism is the same as in the preferred form. Additional rods 100 are mounted in depending bracket arms 46 and supported in an approximately horizontal plane. Blocks 60^a are mounted upon the rods 100 so as to be adjustable thereon longitudinally 55 of the machine. These adjustable blocks 60^a carry auxiliary upper feed wheels 63 which are journaled upon rock arms 62 pivotally mounted upon pins 61 in the same manner as in the preferred form of 60 the invention. In this modified form of the invention, however, each upper curved guide plate 45^a is formed with a longitudinal slot extending almost its entire length so as to permit the friction wheel 63 to rest in peripheral contact with the frictional feed

70 belt 90 in various positions of adjustment. In this modified form of the device the friction wheels 63 rest constantly in operative position and are not intermittently raised as in the preferred form. The straightening gages 75 are constructed and operated in the same manner as above described in connection with the preferred form of the mechanism.

The operation of the feeding machine 75 equipped with my improvements will be clear from the following explanation. It will be understood that the operating mechanism is so arranged that the feeding-off devices 32 are given a reciprocating motion 80 above the pile of sheets and that the drop roller delivery mechanism is timed to operate alternately with the feeding-off devices. The feeding-off fingers engage the top sheet of a pile and move it forwardly above the constantly running underfeed wheels 10 and 55, the main drop rollers 15 being held in elevated position, and the auxiliary frictional feed wheels 63 being in peripheral contact with and driven by the auxiliary underfeed wheels 55. When this preliminary feeding-off stroke takes place the sheet straightening gages 75 are in operative position as shown in Fig. 2 of the drawings. The moment the leading edge of the sheet is engaged between the upper and lower frictional wheels of the auxiliary feeding devices, it will have an added forward impulse imparted to it to carry a sheet into engagement with the straightening gages 75. 90 If the sheet moving from the pile has its leading edge presented squarely at right angles to its direction of travel, then both the straightening gages will be simultaneously engaged by the leading edge of the sheet and both auxiliary feeding devices will operate idly upon the sheet without further change in its position until they are thrown out of action. If, on the other hand, the leading edge of the sheet is not advancing 100 squarely, one of the auxiliary feeding devices will continue to operate after the other has ceased to move the sheet, with the result that the sheet will be squared by its engagement with the straightening gages. 105 These auxiliary feeding devices act upon the sheet only momentarily since they are never called upon to move a sheet more than 1½ inches, or just sufficiently to correct any inequality in the position of the sheet as it is forwarded from the pile by the feeding-off devices. Immediately following the straightening of the sheet against the gages, the drop roller delivery mechanism is brought 110 into action and simultaneously the straightening gages are moved out of the path of the sheet and the auxiliary feeding devices are thrown out of action, so as to permit the sheet to be fed in its straightened condition from the pile of the paper feeder onto 115 120 125 130

the sheet conveyer which carries the sheet squarely forward to the gages of the press or other machine. This operation is repeated for each sheet when it is fed from the pile.

5 The modified form of apparatus shown in Fig. 5 accomplishes substantially the same result as the preferred form although in a slightly different manner. In this modified form the friction wheels 63 always remain 10 in active position but the main delivery drop rollers and straightening gages operate alternately as in the preferred form. In the modified form the supporting blocks 60^a of the upper friction wheels 63 can be adjusted 15 longitudinally of the machine to engage the leading edge of the sheet sooner or later in the feeding operation, depending upon the conditions of the pile and the character of the paper being operated upon, some conditions 20 requiring a greater straightening effect than others.

It will be observed that the upper auxiliary frictional wheels 63 are pressed very lightly against the sheets for feeding them 25 forward. The frictional engagement of the auxiliary devices with the sheet is only sufficient to move them in contact with the straightening gages, but is not sufficient to buckle the sheets or injure their leading 30 edge. The upper and lower guide plates effectively confine the sheets between the auxiliary frictional devices and the straightening gages so as to further insure against objectionable buckling or bending of the 35 sheets.

The great advantage resulting from my improved mechanism is due to the simplicity of the structure and the effectiveness of the arrangement, whereby the rapidity of 40 operation of the automatic feeding machine for properly supplying sheets to the rapid rotary presses in use today is not interfered with, while at the same time the inaccuracies in the position of the successive sheets of a 45 pile are corrected without loss of time between the actions of the feeding off devices and the sheet delivery mechanism.

What I claim is:

1. In a paper feeding machine, the combination of a support for a pile of sheets, feeding off devices operating above the pile, sheet straightening gages arranged at the delivery end of the machine transversely of the line of feed, auxiliary feeding devices 50 arranged to receive the leading edge of sheets moved from the pile by said feeding off devices and feed the same forward until arrested and squared by said gages, suitable delivery mechanism and means including the delivery mechanism for moving said auxiliary feeding devices into and out of operative position.

2. In a paper feeding machine, the combination of a support for a pile of sheets, feeding off devices operating above said support,

sheet straightening gages arranged at the delivery end of the machine transversely of the line of feed, friction rollers arranged to receive the leading edge of sheets moved from the pile by said feeding off devices and feed the same forward until arrested and squared by said gages, suitable delivery mechanism, and means including said delivery mechanism for moving said friction rollers into and out of operative position.

3. In a paper feeding machine, the combination of a support for a pile of sheets, feeding off devices operating above said support, sheet straightening gages arranged at the delivery end of the machine transversely of the line of feed, auxiliary feeding devices arranged to receive the leading edge of sheets moved from the pile by said feeding off devices and feed the same forward until arrested and squared by said gages, suitable guides confining the sheet to the action of said auxiliary feeding devices, suitable main delivery mechanism and means including said main delivery mechanism for moving said auxiliary feeding devices into and out of operative position.

4. In a paper feeding machine, the combination of a front gage, an auxiliary feed roll disposed to feed a sheet against said gage, a rock shaft provided with an arm adapted to raise the auxiliary feed roll out of operative position, and a main feed roll moved into and out of operative position, by said rock shaft.

5. In a paper feeding machine, the combination of laterally spaced front gages, correspondingly spaced auxiliary drop rollers adapted to act independently of each other to force a sheet into alinement against said gages, main drop rollers adapted to deliver 100 a sheet past said gages, and means for intermittently raising and lowering both sets of said drop rollers, said means being adapted to hold the main drop rollers elevated when said auxiliary drop rollers are operative and vice versa.

6. In a feeding machine of the character described, the combination of laterally spaced front gages, laterally spaced auxiliary drop rollers for setting a sheet against said front gages, main drop rollers for delivering a sheet past said gages, and means operated with said main drop rollers for raising said auxiliary drop rollers when the main drop rollers are down.

7. In a feeding machine of the character described, the combination of laterally spaced front gages, auxiliary drop rollers adapted to feed a sheet to aline with said gages, rock arms carrying said rollers, main drop rollers for delivering a sheet past said gages, a rock shaft therefor, and fingers rigid on said rock shaft and adapted to raise and lower said auxiliary drop rollers alternately with the main drop rollers.

8. In a feeding machine of the character described, a rock shaft, a main drop roller carried thereby, a front gage, an auxiliary drop roller for feeding a sheet up to said front gage, an oscillatable lever for carrying said auxiliary drop roller, said lever being provided with a projection, and a lever
- arm mounted on said rock shaft and adapted to engage said projection when said main drop roller descends.
